J. ROMANO

TOY NOVELTY

Filed May 23 1927

UNITED STATES PATENT OFFICE.

JOHN ROMANO, OF BROOKLYN, NEW YORK.

TOY NOVELTY.

Application filed May 23, 1927. Serial No. 193,604.

This invention relates to improvements in toy novelties and has particular reference to a combined hand mirror, fan, and toy balloon.

5 The primary object of the invention resides in the provision of a toy novelty having mirrors on opposite sides thereof together with a grotesque or humorous picture, and fan sections normally disposed within 10 the body and having manipulating portions extending beyond the body and which co-act with the picture to form a part thereof, said manipulating portions being concealed within the body upon movement of the same 15 to extend the fan sections therefrom and which fan sections co-act with the picture to change the general appearance thereof.

Another object of the invention is to provide a toy balloon in a novelty of the above 20 kind, in which a tube extends into the body with the mouth piece of the tube opening on to a handle member extending from the body, while a toy balloon is attached to the opposite end, the said balloon adapted to 25 rise above the body when inflated to add to the amusement of the grotesque picture on the body thereof.

A further object of the invention is to provide a toy novelty of the above kind 30 which is simple of construction, inexpensive of manufacture, and amusing and useful for the purposes intended.

With these and other objects in view, the invention resides in certain novel construction and combination and arrangement of parts, the essential features of which are hereinafter fully described, are particularly pointed out in the appended claim, and are illustrated in the accompanying drawing, in 40 which:

Figure 1 is a perspective view of my improved novelty toy.

Figure 2 is a vertical sectional view therethrough.

45 Figure 3 is a horizontal sectional view on the line 3—3 of Figure 1.

Figure 4 is a front elevation with the fan sections extended.

50 Figure 5 is a front elevation with the balloon in an inflated condition.

Referring more particularly to the drawing, the reference numeral 10 designates my improved novelty toy in its entirety which includes a body portion 11 and a handle

portion 12 which extends from said body 55 portion. The body and handle are made up of a pair of identical flat pieces 13, 13 of stiff cardboard or the like material but the side edges are adhesively secured together for a distance slightly above the handle portion, so as to leave the side edges thereabove 60 open for a purpose to be presently explained. The outer side face of each of the flat pieces 13 is provided with a picture of a grotesque head 14 and in the present instance, the 65 picture represents the head of a man with his mouth wide open. Fixed to the opposite sides of the body to fit within the confines of the mouth are mirrors 15 whereby the article may be used as a hand mirror by 70 grasping the handle portion 12.

Pivoted between the pieces 13, 13 by eyelets 16 are fan sections or panels 17 of a shape to normally fit within the confines of the side edges of the body so as to be concealed therein and which fan sections are provided with manipulating tabs or portions 18 which normally project beyond opposite sides of the body and co-act with the picture thereon to suggest side whiskers. 75 However, when the manipulating portions 18 are pushed inwardly to extend the fan sections 17, the same are concealed within the body while the fan sections serve as the ears of the figure head and serve to increase the 80 area of the article for use as a fan. The concealing of the manipulating portions 18 suggestive of whiskers, and the exposing of the ears or fan sections changes the 85 general appearance of the figure and creates 90 a certain amount of amusement.

Extending from the free end of the handle 12 and extending into the body is a tube 19 to which the neck of a rubber toy balloon 20 is attached. The balloon extends out of the top of the body and when in deflated condition, the same hangs downward therefrom, but when inflated by blowing through the mouth end of the tube, the same rises above the figure head to add to the amusement thereof. The balloon may be held inflated by placing the figure over the mouth end of the tube, or by inserting a stopper therein.

What is claimed as new is:—

105 An article of the class described comprising a body portion having a handle portion extending therefrom, a grotesque picture on

said body portion, a pair of sections pivotally mounted within said body portion and normally concealed therein and being indicative of the ears of said grotesque figure 5 when moved to an exposed position, and manipulating portion extending from said sections beyond the sides of said body portion and movable within said body portion

upon actuation of the same to move said sections to an exposed position on opposite 10 sides of said body portions, said manipulating portions co-acting with said picture to form a part thereof.

In testimony whereof I hereby affix my signature.

JOHN ROMANO.
